UNITED STATES PATENT OFFICE.

JOSEPH H. FINK, OF NEW YORK, N. Y.

DESIGN FOR A FINGER-RING.

SPECIFICATION forming part of Design No. 30,455, dated April 4, 1899.

Application filed February 17, 1899. Serial No. 705,893. Term of patent 7 years.

To all whom it may concern:

Be it known that I, JOSEPH H. FINK, a citizen of the United States, and a resident of New York, (Brooklyn,) county of Kings, and 5 State of New York, have invented and produced a new and original Design for Finger-Rings, of which the following is a specification, reference being had to the accompanying drawing, which represents a perspective 10 view of my newly-designed finger-ring.

The leading feature of my design consists of a ring having a head composed of a central field a , surrounded by a beveled rim a' ,

across which extend representations of triangular cramps a^2 . Between the cramps the 15 rim is embellished by scrolls, while the body of the field a is provided with a star-shaped setting a^3 , as shown.

What I claim is—

The design for a finger-ring, substantially 20 as herein shown and described.

JOSEPH H. FINK.
